US0D1036196S

(12) **United States Design Patent** (10) **Patent No.:** **US D1,036,196 S**
(45) **Date of Patent:** **** Jul. 23, 2024**

(54) **SPOUT**

(71) Applicant: **Runway Blue, LLC**, Alpine, UT (US)

(72) Inventors: **David O. Meyers**, Layton, UT (US);
John R. Omdahl, II, Lindon, UT (US);
Daniel Kendall Harden, Palo Alto, CA
(US); **Elliot Lucas Ortiz**, San
Francisco, CA (US)

(73) Assignee: **Runway Blue, LLC**, Alpine, UT (US)

(**) Term: **15 Years**

(21) Appl. No.: **29/880,031**

(22) Filed: **Jul. 17, 2023**

Related U.S. Application Data

(63) Continuation of application No. 29/842,537, filed on Jun. 14, 2022, now Pat. No. Des. 996,897, which is a continuation of application No. 29/768,922, filed on Feb. 2, 2021, now Pat. No. Des. 955,166, which is a continuation of application No. 29/731,210, filed on Apr. 13, 2020, now Pat. No. Des. 911,104, which is a continuation of application No. 29/602,291, filed on Apr. 28, 2017, now Pat. No. Des. 884,416.

(57) **CLAIM**

The ornamental design for a spout, as shown and described.

DESCRIPTION

FIG. 1 is a top front perspective view of a spout, showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate environmental structure and parts of the article that form no part of the claimed design. The dot-dash broken lines illustrate boundaries of the claimed design and form no part of the claimed design.

1 Claim, 8 Drawing Sheets
